UNITED STATES PATENT OFFICE.

EDWARD E. CLEMENT, OF WASHINGTON, DISTRICT OF COLUMBIA

TELEPHONE-EXCHANGE SYSTEM.

1,107,152.

Specification of Letters Patent. Patented Aug. 11, 1914.

Application filed December 26, 1907. Serial No. 408,039.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawing.

10 My invention relates to telephone exchange systems, and has for its object the improvement and simplification of such systems.

In order to attain my object I make use 15 of an automatic connective apparatus and manual means for initially starting the proper automatic connective apparatus for effecting the connection between a calling and a called subscriber.

20 Briefly stated, my invention comprises subscribers' lines terminating in the contacts of relays. These relays are divided into groups, each group containing on one side the multiple terminals of lines and on the 25 other side the terminals of a trunk. These relays I have designated as the tens and units relays. Associated with each group of tens relays is a group of units relays. When a line is calling one of the tens relays and one 30 of the units relays in an idle group are actuated and on pulling up serve to connect the calling line with their trunk. These trunks are fewer in number than the lines. Ordinarily these are one hundred lines to every

35 ten trunks. When the calling line has been connected with an idle trunk the fact is communicated to an operator by means of a signal either visual or aural and after ascertaining the number wanted she 40 sets up this number on a key set which resembles in its appearance the key set of an adding or calculating machine. After the keys corresponding to the numbers have been depressed they remain locked in 45 their depressed position until released by the setting up of another number. The depression of these keys connects an impulse sending device with the trunk to which the subscriber has been connected. Now by

50 means of impulses sent out from the sending device another trunk is selected for the further continuation of the connection between the calling and called subscriber. The selection of this trunk is effected partly by 55 means of an automatic switch and partly by

means of tens and units relays. A second trunk for effecting another step in completing the connection between the calling and the called subscriber is selected in the same manner that the immediately preceding 60 trunk was selected. Finally the connection with the called subscriber's line terminals is effected by means of two automatic switches and a set of tens and units relays.

A further object of my invention is to 65 provide means whereby the connections described above may be effected by means of different key sets, that is by key sets at different operators' positions. To this end I may make use of either a selective switch 70 for selecting a calling line together with devices for rendering the switch inoperative when its associated key set is in use or I may employ relays for the same purpose.

A further object of my invention is to 75 provide means whereby idle trunks may be selected in rotation. Thus when the first idle trunk is selected the actuation of certain relays associated with it puts the next trunk in condition for use while at the same time 80 rendering the busy trunk inoperative for any other call that may come in. The second trunk then puts the third trunk in condition for operation and also cuts it off from any interference from a subsequent incoming 85 call until conversation has ceased and the trunk is again restored to its normal condition.

A further object of my invention is to 90 provide a telephone exchange system with connective apparatus and manual means for controlling the operation of the connective apparatus which is particularly adapted for the employment of blind operators. For this purpose I provide signals which may be 95 connected with any operator's head set or placed upon the operator's transmitter or otherwise disposed so that the indication of the call may be communicated to the operator by the sense of touch or hearing. The 100 manipulation of the number keys is all that is required of the operator after the number is learned and the provision of the aural or touch signal is all that is necessary to render the system particularly adapted for blind operators. The use of these signals and the arrangement of a switchboard or keyboard for the blind is of course not confined to the specific apparatus or system of connection hereinafter described, but may be ap- 105 110

plied to any system of my own or others which will otherwise meet the necessities of the case.

Other objects and advantages will appear in the detailed description of the system and of the particular parts and pieces of apparatus used therein.

My invention is illustrated in the accompanying drawings in which:

Figure A is a diagram of a complete system embodying my invention, with all details omitted; Fig. B is a diagram of diagrams showing how to piece together the following figures to form the complete lay out of the system in detail; Fig. 1 shows three typical subscribers' stations; Fig. 2 shows the terminal apparatus of three subscribers' lines and the first tens relays of three groups pertaining to three separate trunks; Fig. 3 shows the terminal apparatus of three other subscribers' lines and the second tens relays of the same three groups of relays pertaining to the same trunks of Fig. 2; Fig. 3^a shows the first three tens relays of a group of relays pertaining to a particular trunk, together with the line terminals in said relays and a full set of units relays associated with the particular trunk; Fig. 3^b shows the relation of the multiple line terminal connections of the various groups of tens relays; Fig. 4 shows the first three units relays of the first three groups and the trunk connections effected thereby; Fig. 5 shows a portion of a connective trunk circuit and an automatic switch associated therewith; Fig. 5^a shows a side view of the automatic switch associated with the trunk shown in Fig. 5; Fig. 5^b shows a plan view of the switch; Fig. 5^c shows an end view of the switch; Fig. 5^d is a detailed sectional view of a portion of the switch on the line 5—5 of Fig. 5^a. Fig. 5^e is an end view of the contacts shown in Fig. 5^a; Fig. 5^f is an enlarged detailed view of the pawl and dog shown in Fig. 5^a; Fig. 6 shows a secondary selector switch and part of an operator's set; Fig. 6^a is a fragmentary diagram showing the operator's set with special signal arrangement for blind operators; Fig. 7 shows part of an operator's sending device; Fig. 7^a shows the remaining part of the operator's sending device and is a continuation of Fig. 7; Fig. 7^b is a side view of a key strip; Fig. 7^c is an end view of the same; Fig. 7^d is a top plan view; Figs. 7^e and 7^f are details of a modified form of key use being made of a side roller engaging the circuit contacts instead of a cam inclined block as in Fig. 7^b; Fig. 8 shows a set of tens and units relays which constitute part of the automatic second selector trunk; Fig. 9 shows a second trunk circuit and an automatic switch; Fig. 10 shows a set of relays similar to that shown in Fig. 8 and constituting part of a second selector device;

Fig. 11 shows a third trunk together with two automatic switches; Fig. 12 shows a set of relays constituting part of the automatic connector; Fig. 13 shows portions of three trunk circuits and the manner in which automatic selection of trunks is effected; Fig. 14 shows three trunk circuits and three operators' sets and illustrates the manner in which the operators' sets are selectively connected.

Fig. A is intended to show the general arrangement of the system hereinafter described. For the sake of clearness all details such as relays, switches, contacts, etc., have been omitted the idea being to show at a glance the general scheme employed in effecting the talking connection between a calling and a called subscriber. Two subscribers' stations are shown at the left of the figure. Their line circuits (which are denoted by a single line for the sake of clearness) are shown multiplied to the various groups of primary selector relays, the tens relays of said groups being denoted by N, 1N, 2N, and the units relays by P, 1P, 2P. The purpose of the primary selector relays is to connect a calling subscriber with an idle trunk leading to the first selector relays which in this case are denoted by E, F, 1E, 1F, 2E, 2F. The manner in which this is done will be fully explained hereinafter. It will suffice to say that the primary selector relays automatically connect a calling subscriber with an idle trunk. It will be seen from the figure that the operators' sending sets are connected with the first trunk. These sets are brought automatically into operation when connection is effected with the first trunk. By means of impulses sent from the operators' sets the first selector switches X', 1X' or 2X' according to which trunk has been selected, are operated to select a set of relays belonging to a particular group of trunks leading to the second selector relays which then picks out and makes connection with an idle trunk of that group in a manner similar to that of the primary selector relays. The connection is now completed to the second selector switches. Other impulses are now sent out from the operator's set and these switches and the second selector relays operate in precisely the same manner as the first selector switches and first selector relays to select and connect with an idle trunk leading to the connector switches and connector relays denoted in general by X² and X⁴ and I and U. Finally impulses are sent to the switch X² to select a group of tens relays I and impulses are sent to the switch X⁴ to select a group of units relays U. The pulling up of these two sets of relays I and U finally effects connection with the multiple terminals of the wanted subscriber.

Referring to Fig. 1, I have shown therein

three subscribers' stations, A, A¹ and A², each equipped with a telephone transmitter T, a receiver R, a switch hook, a ringer Q, and a condenser C, all of the usual or suitable type for use with common battery circuits. When the hook is up, that is when weight of the receiver is removed the circuit is through the transmitter and the receiver; and when the hook is down, the line circuit 10 is completed for alternating current only, through the ringer and condenser.

Since the circuits are the same for all the lines, I will refer to the line from station A only. This consists of conductors 1 and 2, 15 extending from the sub-station to the central office. At the sub-station the talking circuit is completed through the wires 3—4 when the hook is up, and the ringing circuit through the wires 5—6 when the hook 20 is down. These figures are useful for the purpose of tracing the circuits only.

Turning to Fig. 2, the line wires 1 and 2 appear at the left hand side of the figure, terminating in contacts of the cut-off relays 25 M', which are normally deenergized, so that in each case the line wire 2 is normally grounded at 7 through the wire 7^a, and the line wire 1 is extended through the line 8 to the line relay M and so to main battery B 30 and to ground through the wire 8^a. The armature m of each line relay M is connected to battery B through the conductor 8^a, and when attracted is adapted to close upon the terminal contacts of wires leading to the 35 tens and units relays of the primary selector sets.

I preferably divide all the incoming lines in an exchange, into groups of say one hundred each, and to each group I apportion a 40 fixed number of trunks leading to connective apparatus. In a small or comparatively inactive exchange the percentage of these trunks may be as low as five and in large exchanges it may be raised to ten or even 45 fifteen. I assume however that ten per cent. of connective apparatus will be sufficient to care for the present system, hence I provide ten trunks for each one hundred lines, and a complete set of tens and units relays 50 in a primary selector group for each trunk. The circuits herein illustrated show six lines, which for convenience I will call numbers 500, 501 and 502, Fig. 2, and 510, 511 and 512, Fig. 3. The subscribers' circuits of 55 Fig. 1 will fit any of these, and in order to fully comprehend the connections of these lines and the arrangement of the tens and units relays, it is necessary to consider Figs. 2, 3 and 4 together. In Figs. 2 and 3 the subscribers' extension lines are shown coming into their initial terminals on the tens relays which are of the type shown in my prior application, Serial No. 306,292, filed March 15th, 1906. Each of these relays carries the 60 terminals of ten lines and for each trunk there

are ten of these relays, so that for one hundred lines provided with ten trunks there will be one hundred ten-point relays containing one thousand pairs of line terminals, from which it appears that each line can be 65 multiplied ten times, which it should be in order to obtain access on occasion, to every one of the ten trunks. The contacts on the ten-point relays are arranged to duplicate pairs, that is, the incoming lines terminate 70 each on one pair of springs, opposite which, another pair of springs appears to which the line is connected when the relay is energized, and from which a local circuit passes to the front contact springs of a particular units 75 or single-point relay. For each group of ten tens relays there are ten units relays, or twenty relays in all for each trunk.

In order that the multiple connections of the line terminals may be thoroughly understood attention is called to the Figs. 3^a and 3^b. In Fig. 3^a there are shown the first three tens relays of a set of ten associated with one particular trunk and also the ten units relays belonging to the same trunk. The first relay N contains the terminals of the lines numbered 500 to 509 inclusive; the second relay N' contains the terminals of the lines numbered from 510 to 519 inclusive; the third relay N² contains the terminals of the lines numbered from 520 to 529 inclusive. Any one of the tens relays can be connected to the trunk 30—31 by the coöperation of one of the particular units relays belonging to the trunk. Thus, if the 100 relay N' should be operated and one of the relays, say P⁷, line 517 would be connected to the trunk 30—31, the operation of the relay N' would connect all the lines of the group N' to the multiple wires 600 and the 105 pulling up of the units relay P⁷ would connect the trunk 30—31 with the particular set of wires 650 corresponding to the line 517.

In Fig. 3^b I have shown the multiple connection of the terminals in relays belonging to the various trunks. In order to simplify the drawing I have shown only the first two tens relays of the first four trunks. The first line 500 is multiplied to the first 110 pair of contacts of the first tens relay of each trunk by the wires 651 and 652. The next line No. 501 is multiplied to the second pair of contacts in the first tens relay belonging to each trunk by the wires 661 115 and 662. Similarly the lines 520 and 521 are multiplied to the first and second pairs of contacts, respectively, of the second relays belonging to the various trunks by the wires 671, 672 and 681, 682. This arrangement is continued throughout the ten groups of relays belonging to the ten trunks.

In Fig. 2 I have shown the terminal ends of lines 500 to 529 inclusive, connected to a pair of contacts n³, n⁵. In Figs. 2 and 130

3 only five pairs of contacts n^3 , n^5 are shown with each tens relay, but it is to be understood that there are ordinarily ten pairs of these contacts as shown in Fig. 3^a. For lines 500 to 509 the line terminals are in the relay N. For lines 510 to 519 they are in the relay N', and for lines 520 to 529 they are in the relay next in order, and so on. Thus each relay contains line terminals n^3 , 10 n^5 for ten lines. When any one of the lines appropriated to a particular relay is calling, the electromagnet n' of that relay becomes energized. This will be explained in connection with the circuits of Figs. 1 and 15 2 farther on. For example, if any line from 500 to 509 originates a call the magnet n' of the relay N will become energized and simultaneously connect all of the lines from 20 500 to 509 on to the extensions 10 to 19, inclusive, shown at the bottom of Fig. 2. If, however, the calling line is in the group 25 510 to 519, the magnet n' of the relay N' will become energized connecting all that group on to the extensions 10 to 19, inclusive. Similarly if the calling line be in the third group from 520 to 529, the magnet n' of the relay N² will be energized connecting the entire group on to the extensions 10 to 19, inclusive. Thus extensions 10 to 30 19 are seen to be common to all of the tens relays, and in fact each extension pair is multiplied to corresponding contacts in all of the tens relays. Number 10 extension goes to the first pair of contacts n^4 , n^6 in 35 each of the relays N, N', N². Extension No. 11 is multiplied to the second pair of contacts n^4 , n^6 in each of the relays, and so on with all the extensions, up to number 19.

In Fig. 4 I have shown three units relays 40 of each set. I have assumed the numbers 500, 501 and 502 for the lines entering Fig. 2, and 510, 511 and 512 for the lines entering Fig. 3. The first three lines, being within 45 the same tens digits of each other, go into the same tens relays in each set. For the sake of convenience I have given the designating numerals of the relays coefficients and have marked the three trunks in Fig. 4 so as to be readily followed. Thus in Fig. 50 2 all three of the lines come into the relay N, which is adapted to put them onto the extensions 10, 11, 12, etc., leading to the units relays P, P', P², etc., in Fig. 4. Each 55 of the lines 500, 501 and 502 not only terminates in contacts of the relay N but is multiplied to similar contacts in the relays 1N, 2N, etc., as has been explained before. There would be one of these added for each 60 trunk that is appropriated to a group of lines. In the present case I only illustrate three trunks so that each line need be multiplied only three times.

In Fig. 3 the lines 510, 511 and 512 are 65 connected to the tens relays N', 1N', 2N' in the same manner as the lines in Fig. 2,

each line being multiplied three times so that each may have access to any one of the three trunks. It will be understood of course that the relays N, N' of Figs. 2 and 3 and P, P', P² of Fig. 4 constitute one set appropriated to the trunk 30-31. Similarly the relays 70 1N, 1N', 1P, 1P', 1P², all belong to one set appropriated to the trunk line 130-131. Similarly again, the relays 2N, 2N', 2P, 2P' and 2P² belong to one set appropriated to the trunk line 230-231. The extensions 75 from the tens relays to the units are marked 10, 11 and 12 for the first set, 110, 111, 112 for the second set, and 210, 211, 212 for the third set.

The actual connections controlled by the relays N and P being thus understood, it is most important to explain the means by which I control these relays. Referring to Fig. 2, the line wires 1 and 2 terminate as I have stated, in the contacts of the cut-off relay M', through which they are normally connected to the line relay M and battery B. When the subscriber at station A takes the telephone receiver from the hook, he closes his line circuit, the line relay M is energized and the two branch circuits 50 and 51 are immediately closed. The branch 50 passes in multiple to one winding of each of the three tens relays N, 1N and 2N, these relays 80 being double wound for the purpose of making them self-locking when attracted. Any one of these relays might thus be energized by any one of the three lines shown, but it is my purpose that only one of them shall be so energized at once, and that no two lines shall be able to energize the same relay at the same time. Hence on the other side of these relays I take away the circuit wires 85 which are designated generically by the numerals 54, 55 and 56, to three separate controlling means in the shape of special relays associated with the switch trunks. One of these relays is shown at D^x in Fig. 5. Each 90 of the first named relays has its locking winding 100 connected through one of the wires indicated by 57, 58 or 59, to controlling means similar to those I have just mentioned and which will also be described later.

The wires leading to the units relays are marked 51 for the line 502, 52 for the line 501 and 53 for line 500. The three wires 105 51, 52 and 53 pass along the bottom of Figs. 2 and 3 and into Fig. 4 where they terminate in the first or operating windings of the three relays P, P' and P², also by multiples 110 in the corresponding windings of the relays 1P, 1P', 1P² and 2P, 2P' and 2P². The three relays P, P', P² since they belong to the same set, have a common control, their return wires 54^a, 54^b and 54^c passing to contacts in the twenty pair relay D^x in Fig. 5. 120

This relay controls the return wires of both the tens and units relays of this set, twenty in all.

Each of the units relays in Fig. 4 has a locking winding separate from the actuating winding and each locking winding terminates on one side in a contact normally open but adapted to be grounded when the relay is energized. All the locking windings of the first set or group have a common return 5 wire 61, passing on to the wire 57 which is the control wire of the locking windings on the tens relays N, N'. This wire 57 passes into Fig. 5 and is there carried to a pair of trunk 10 relays by which it is controlled.

The actuating windings of the units relays 1P, 1P', 1P² have return wires 62, 62^a, 62^b, passing to the contacts of a relay 1D^x for trunk 130—131 similar to the relay D^x of 15 trunk 30—31. The trunks 130—131 and 230—231 are not shown in Fig. 5, since the trunk 30 is typical of other trunks and a description of it will suffice for an understanding of the system. The locking windings of the relays 20 1P, 1P' and 1P² have a common return wire 63 which goes to the wire 57 corresponding to the wire 57 and controlled like the latter by relays associated with the trunk 130—131. Similarly the actuating and locking 25 windings, respectively, of the units relays 2P, 2P' and 2P² have their return wires passing to relays in the trunk 230—231 and are controlled thereby. The working of the apparatus thus far described will be set 30 forth at length in the operation of the system.

A portion of the trunk circuit 30, 31 including a first selector switch X is shown in Fig. 5. In order to render the description 40 more intelligible, I have designated certain portions of the trunk circuit 30, 31 in Fig. 5 with reference numerals; thus on the tip side are the conductors 14 and 15 separated by the condenser C' and the extension 16, 45 while on the sleeve side are the corresponding conductors 17 and 18 separated by the condenser C² and the extension 19. Across the answering end of the trunk are bridged the two relays R⁷ and R⁸, with the main 50 battery B between them. The trip relay R⁸ is grounded when the sleeve relay R⁷ is connected to the live side of battery, which is the usual arrangement in circuits of this type. The relay R⁹ has its circuit controlled 55 by both the relays R⁷ and R¹⁰, the latter relay serving when actuated to sever the trunk circuit and when deenergized to again restore it. Relay R¹¹ is a cut-off switch relay 60 for the first selector switch X and its circuit is controlled through a contact on the relay R¹² which is in turn controlled by the relay R¹⁰. Before passing from Fig. 5 I wish to call particular attention to the form of the selector switch X. This is clearly illustrated 65 in Figs. 5^a, 5^b, 5^c, 5^d, 5^e and 5^f.

Referring to Fig. 5^a, the switch is designated in general by X. It comprises a supporting frame of strap iron 101 bent into a U-shaped form and fastened at its free ends to a vertical crosspiece 102, preferable of 70 brass, by means of the screws 103, 104, which pass through outwardly turned flanges 105 and 106 and secure the latter firmly to the crosspiece. The vertical crosspiece 102 has a rectangular opening therein extending 75 from front to the rear side thereof. Within this opening are secured the two vertical rows of separate contacts, 108, 109, and the two continuous contact strips 110 and 111 together with the terminals 112 and 113. 80 Suitable insulation 114 is provided and the contacts together with the insulation are firmly secured in place by means of screws 107. A movable rack 115 is disposed in 85 openings 116 in the top and bottom pieces of the frame 111. This rack bears wipers 117 adapted to engage the contacts in the rows 108, 109, 110 and 111 successively as the rack is moved vertically. The stepping up of the rack is accomplished through the 90 medium of the magnet V^m, which is attached to the upper part of the frame. This magnet has an armature 118 pivoted at 119 to ears 120 secured to the frame 111, by means of the screws 121. This armature is held in 95 normally retracted position by means of the spring 122 and its movement may be limited by means of the screw 123. A pawl 124 is pivotally mounted at the free end of the armature 118. The upper end of the pawl projects through an opening 125 in a vertically extending crosspiece 126 secured between the upper and lower portions of the frame 101, and is kept normally in engagement 100 with the teeth of the rack by means of a spring 127. Disposed in a reduced portion of the opening 125 is a retaining dog 128. The latter is secured to an L-shaped member 129 provided with an opening 130. The L-shaped member 129 is in turn secured 105 to a leaf spring 131, the opposite end of which is attached to the lower part of the cross member 126. The tension of the spring 131 keeps the dog in engagement 110 with the teeth of the rack, the beveled end of the dog riding over the teeth as the rack is stepped up. The release magnet R^m is secured at one end to the crosspiece 126. At the opposite end of the magnet the armature 132 is pivotally suspended at 133 from the ears 134 which are secured to the upper 115 part of the frame 111 by means of the screw 135. At the lower end of the armature 132 there is secured a light spring member 136 provided with a downwardly turned end 137 arranged to enter the opening 130 when the armature 132 is attracted. The upper end of the armature 132 projects past its pivotal point and to the upper end is attached a spring 138 which keeps the armature 120 130 attracted.

ture in a normally retracted position. The adjustable screw 139 in the end of the armature 118 of the vertical magnet is arranged to engage the spring member 136 when the vertical magnet is energized to lift said spring member out of engagement with the opening 130 in the L-shaped member 129, in the manner hereinafter explained.

- 5 An insulating block 140 is carried by the frame 101 and supports the ends of the contact terminal pairs 141 and 142. The block 140 bearing the springs 141 and 142, together with the terminals 112 and 113 form a "plug" and "jack" device. An inspection of Figs. 5^a and 5^b will show that the terminals 112 and 113 are curved outwardly at their ends. Toward the inner ends of these terminals there is a separate companion piece 143, also having its free ends 15 curved outwardly and forming with the terminal a jack member adapted to receive the terminal held in the insulating block 140. The utility of this arrangement may be understood more readily when one considers that the cross member 102 is intended to be attached securely to the supporting frame by means of screws which are adapted to enter the openings 144 and 145 in the top and bottom, respectively, of the 20 crosspiece 102. By withdrawing the screws 103 and 104 the switch mechanism may be removed from the supporting cross piece 102 and in replacing it again the terminals 140, 141 enter between the springs 112, 143 25 and form contact with them in the same manner as the ordinary plug and jack thereby greatly facilitating the assembling of these switches on their respective frames, and their repair or adjustment.
- 30 40 The operation of the switch may be easily understood from the foregoing description of the various parts. A predetermined number of current impulses, say five, is passed through the vertical magnet. At 45 each impulse the armature 118 is attracted and the pawl 124 forces the rack 115 upward one step by means of its engagement with a tooth of the rack. On the interruption of the circuit the armature 118 is retracted by the spring 122, and the beveled end of the pawl riding over the tooth of the rack while the dog 128 keeps the rack in its stepped up position. At another impulse 50 the same operation is repeated until finally the wipers 117 on the rack are brought into engagement with the fifth contact pieces of the vertical rows.
- 55 The release of the switch and its restoration to normal is accomplished by the release magnet R^m. At the appropriate time a single impulse is sent to this magnet, the armature 132 is attracted and the downwardly turned hook 137 of the spring 136 drops into the opening 130 of the L-shaped member 129. On the cessation of the actuating cur-

rent the armature, together with the dog 128 is now retracted by the tension of the spring 138 against the tension of spring 131 that normally holds the dog in engagement with the teeth. The withdrawal of the dog 70 permits the rack and its wipers 117 to drop, the wipers assuming a position below the contacts and out of engagement with them. The downward movement of the rack is limited by the engagement of the base 117^a 75 upon which the wipers are carried, with the bottom member of the frame 101. The dog 128 is still held by the spring member 136 out of engagement with the teeth of the rack, and it is only upon a subsequent actuation of the armature 118 that it is released. This is accomplished through the medium 80 of the adjustable screw 139 which lifts the spring 136 out of the opening 130 and permits the reengagement of the dog with the 85 rack teeth.

Referring now to Fig. 6 I have shown therein an operator's equipment and a selector switch for connecting a calling trunk therewith. The selector switch is marked 90 S^w. It has a spindle s' and wipers s², s³, s⁴, s⁵. The spindle is rotated by means of a pawl p¹⁰ and ratchet r¹⁰. The pawl is pivoted to the armature of the relay R² and the ratchet wheel is turned when the relay is 95 energized.

The circuit of the rotary vibrator magnet is closed through a vibrator V^b. The circuit of the magnet R² is controlled by the relay R³ which also controls, through the medium 100 of a contact on its opposite end, the circuit of the signal lamp L. The actuating circuit of the relay R³ is controlled in turn through a contact on the relay R⁴. The operator's 105 ringing key is shown at O. The functions of the relays R⁵, and R⁶ will be fully described in the statement of the operation of the system.

Figs. 7 and 7^a show what I shall call a 110 multiple number transmitter which is common to all the operators in the exchange or to any desired group. This signal transmitter is really an impulse generator or commutator device and is preferably constantly driven, and according to the present practice in such matters, it will be installed in duplicate at least so that no mischance to one machine can stop the entire work of the exchange, which would happen if there were only one machine and it should get out of 115 order. In Fig. 7 I show a set of wheels Q', Q², Q³, Q⁴ and Q⁵, provided with teeth of various sizes. The tooth t' of the wheel Q' being the smallest, the tooth t² of the wheel Q² having twice the contact surface of the tooth t'; t³ having three times the contact surface, and so on. A complete machine 120 will have ten of these wheels so that any digit from 1 to 10 can be started by sending the appropriate number of impulses. In 130

Fig. 7 I have shown the first five number wheels and in Fig. 7^a which is to be taken with Fig. 7, the remaining five wheels of the set. In practice these wheels are all one. 5 The teeth t' , t^2 , t^3 , etc., are formed upon the surface of a drum, which is driven by a suitable motor at a constant speed. The speed which I have found most suitable for this device and for the type of switches I 10 have illustrated, is approximately twelve revolutions per minute. Each wheel is provided with four spring contact pens q' , q^2 , q^3 and q^4 through which the impulses are transmitted through the four sets of keys 15 K' , K^2 , K^3 , K^4 in the order of their numbers. The pen q' of the wheel Q' is connected to the spring 71 of the key k' in the set K' , by means of the wire 72. Similarly the pen q' of the wheel Q^2 is connected to the spring 20 73 of the key k^2 of the set K' by the wire 74 and so on, the succeeding wires being marked 75, 76 and 77, all of which go to the springs of the keys of the set K' . The second set of springs q^2 is connected in the 25 same order to the springs of the keys belonging to the set K^2 ; the third set of springs q^3 are similarly connected to the individual springs of the key set K^3 ; and finally the fourth set of springs q^4 are connected to the individual springs of the set 30 K^4 . On the common shaft of the sending machine is a main commutator C^m having a brush b connected to the main battery B , and riding over its segments so as to produce regular recurring makes and breaks in 35 a continuous series. In practice this commutator is made with a pair of spring contacts and teeth or cams are formed on the body of the commutator to work these springs up 40 and down but for convenience of illustration I have shown the brush in the diagrammatic view in Fig. 5 as riding directly on the periphery of the disk. With such a construction in actual practice and considering 45 that this commutator will carry a large number of switching apparatus simultaneously, I prefer to make a brush b of carbon.

It may be stated here that the size of the 50 teeth on the wheels Q' , Q^2 , etc., bears a definite relation to the teeth of the commutator. Thus, the first wheel Q' has a single tooth t' approximately equal in length to only one tooth on the main commutator C^m . The second wheel Q^2 has a single tooth t^2 approximately equal in length to two teeth in the commutator. It will be pointed out here- 55 after how the contact of the tooth t' of the wheel Q' with a pen sends one impulse from the commutator. The tooth t^2 of wheel Q^2 while in contact with a pen sends two impulses from the commutator. A peculiarity of the arrangement is that the makes and 60 breaks on the number wheels Q' , Q^2 , etc., are made during the passage of gaps on the

main commutator when there is zero potential, and hence there will be no sparking at the number wheel contacts. The larger gaps are arranged to come under the brush b when one of the teeth on the wheel Q^r is in contact with the pen q^r . I have provided a starting wheel Q^s of conducting material provided with an insulating section s in its periphery, and also the wheel Q^r which is insulated from the main shaft S and is provided with four teeth in quadrature arrangement to contact with a single pen for purposes hereinafter explained. The key K^s is a starting key. 70

Fig. 7^b shows a row of keys used in the 80 operators' sets. These keys have been described in a previous application No. 374,644, filed May 20th, 1907. In this figure I have shown a row of ten keys having a common locking bar 23 which is arranged to 85 engage an extension 17 on a lug 15 secured to the spindle 11 of the key. An insulating cam member 18 secured to the member 15 is adapted to engage the upper end of the spring 8 to force it against its anvil 9 to 90 effect connection between the two. The key is retained in its upper normal position by means of the spring 20 while the rod 23 is held against the member 15 by means of the spring 22. It is obvious that by 95 the depression of any key of the set the rod 23 will be moved toward the left thereby releasing a previously depressed key which returns to its normal position under influence of the spring 20 while the latter 100 key is held in its depressed position by the engagement of the extension 17 with the pin 24 on the lug 23.

The switch X already described forms one 105 element of a combination capable of selecting one of a number of idle selector trunks for the further extension of the talking circuit. The other element of the combination comprises two sets of relays for each 110 trunk adapted to coöperate in the same manner as the tens and units relays heretofore described. These two sets of relays are shown in Fig. 8. In this figure the trunk 30, 31 is seen entering from the left and terminating on the first pair of same contacts of the relay E, and being multiplied to the contacts of similar relay sets E, 2E, 3E, etc., of the other trunks. As in the case of the primary tens relays, already described, the armatures of this group when actuated 115 are each adapted to close the contact terminals of a group of ten trunks. In the set of relays shown in Fig. 8 the terminals of only twenty-five trunks appear. Any one of these may be connected with the trunk 30^a, 120 31^a, by coöperation with one of the units relays.

The group of units relays F, F', F², F³ and F⁴ co-act as above stated with the relays E, E', etc., to select a particular trunk. The 130

actuation of the various relays shown in Fig. 8 as well as the working of their locking circuits will be explained hereinafter.

Fig. 9 shows a second selector switch X^2 of precisely similar construction to the first selector switch X' and a portion of the trunk circuit 30^a, 31^a, which is in turn multiplied to the relays of a number of connector trunks, one set of which is shown in Fig. 10. The control relay D^x corresponds to the relay D^x and is arranged to control the circuits in a manner similar to the latter. The relays R^{13} and R^{14} , R^{15} and R^{16} are the tip, sleeve, cut-off, and control relays respectively corresponding to the relays R^8 , R^7 , R^{11} and R^{12} of Fig. 5.

Fig. 10 shows tens and units relays of a second selector trunk the tens relays being designated as G , G' , G^2 , G^3 , and G^4 and the units relays H , H' , H^2 , H^3 and H^4 . The arrangement herein shown is identical with that shown in Fig. 8 and the tens and units relays coöperate with the switch X^2 to form a secondary selecting device in the same manner in which the relays of Fig. 8 coöperate with the switch X' for the first trunk selection.

Fig. 11 shows two switches X^3 and X^4 together with a portion of the connector trunk circuit, 30^b, 31^b. In this trunk are interposed the condensers C^3 and C^4 . The control relay D^x , the tip and sleeve relays R^{17} and R^{18} respectively and the cut-off relay R^{19} have functions similar to the corresponding relays shown in the other figures. R^{24} is a ringing relay arranged to break the circuit and to switch on the ringing generator G_r . This relay is operated intermittently through the commutator C^o and its circuit is controlled by a contact on the relay R^{20} . The circuit of the relay R^{20} is controlled by the relay R^{23} and the actuating circuit of the latter as well as of the relay R^{21} is controlled jointly by the relays R^{17} and R^{18} . The switches X^3 and X^4 are of the same construction as the switches X and X^2 and their workings will be disclosed in the consideration of the operation of the system.

Referring now to Fig. 12 I have shown therein two groups of relays arranged to coöperate with the switches shown in Fig. 11 for effecting connection of the called subscriber with the calling subscriber over the trunks already described. The units relays I , I' , I^2 , I^3 and I^4 are shown directly connected with the trunk while the tens relays U , U' , U^2 , U^3 and U^4 contain the terminals of the individual subscribers' lines. It will be noted that the relays shown in Fig. 12 all pertain to the same trunk as their designation would indicate. The terminal contacts of each subscriber's line which are controlled by the relay armatures are multiplied to corresponding contacts in similar relays

of other groups. Thus it will be seen that if relay I and any of the set U pull up, the first subscriber will be connected; if relay I' and any of the relays in the set U pull up, the second subscriber will be connected, 70 and so on.

From the foregoing description of the arrangement of the system and of the various pieces of apparatus connected therewith the operation should be easily understood. 75

Let us assume that the subscriber at station A in Fig. 1 desires to talk with the subscriber whose number is 2312. When he takes down his receiver his line circuit 1-2 is closed and the line relay M is actuated, 80 the actuating current being from battery B , 8^a, M , 8, m' , 1, 3, T , R , 4, 2, 1^{m'} and ground. The pulling up of the armature m places battery current on the terminals of the wires 50 and 51. Now assuming that all 85 connective apparatus is idle the tens relay N of Fig. 2 and the units relay P of Fig. 4 will pull up. The actuating circuit for the relay N is from battery B (Fig. 2), 8^a, m , 50, N , 54, continuation of wire 54 in Figs. 3, 90 4 and 5 through the closed contacts of the relay D^x and to ground. The actuating circuit of the relay P is from battery B (Fig. 2), 8^a, m , 51, continuation of 51 in Figs. 3 and 4, P , 54^a, and through the closed contacts of the relay D^x to ground. On the energization of the tens relay N the extension wires from the cut-off relay M' are prolonged by way of the contacts 500 and the wires 10 to the trunk 30, 31 in Fig. 4, and 100 thence to a continuation of the trunk in Fig. 5 through the closing of the trunk contacts by the units relay P . Current immediately flows from the main battery B in Fig. 5 through conductor 201, the sleeve relay R^7 105 and back through the sleeve side 17 of the trunk over the path already traced, through the cut-off relay M' and ground. The cut-off relay thereupon immediately pulls up putting the subscriber's line onto the extensions and so onto the trunk 30-31. At the same time current flows from battery through the conductor 200, 201, 202, contact 203 of relay R^9 , 204, and thence on to wire 57 back to the tens relay N and to ground 110 through its armature which has now pulled up thus providing a locking circuit for the tens relay. An inspection of Fig. 4 will show that the common locking wire of the relays P , P' and P^2 connect with the wire 120 57 and since the armature of the units relay P has pulled up this relay is also locked by current from the wire 57 over the locking wire 61 and to ground. On the energization of the cut-off relay M' the tip relay R^8 is 125 actuated, the current flowing from the battery through the sleeve relay R^7 back over the connected trunk through the subscriber's line wires and over the tip side of the trunk through the relay R^8 and to 130

115
120
125
130

ground. The actuation of the relay R^8 removes the locking control from the relay R^9 through the pulling up of the armature 205 of the former relay the current then being supplied to the locking wire 57 from the battery over conductors 200, 201, 206, 205 and 204. The relays N and P remain therefore, subject to the control of the tip relay R^8 which is itself controlled by the scribe at station A. When the sleeve relay R^7 pulls up it puts battery current on the relay D^x through the closing of the contacts 207, 208. The latter then pulls up and cuts off all the return wires 54^a, 54^b, 54^c, etc., of the selector relays N, P, etc., of its set. The trunk is thus disabled for any other calls.

The energization of the relay R^7 connects one side of the starting relay R^z in Fig. 6, 20 to ground by the closure of the contacts 213-214. The other side of the relay is connected to battery through the normally closed contacts 27 and 28' of the relay R^3 . The relay R^z is therefore energized, the energizing current flowing from battery through 215, 216, 27, 28', 217, R^z , 219, 220, 221, 214, 213 and ground. On the pulling up of the armature 221' of the relay R^z , battery current is supplied to the relay R^2 30 (the latter being grounded on one side through the wire 218) through the vibrator a^{10} . The action of the vibrator causes an intermittent current through the relay R^2 . At each impulse the armature a^{10} is pulled up and through the medium of the pawl p^{20} causes the movement of the ratchet wheel r^{10} and the turning of the spindle s' one step. The ratchet wheel r^{10} is held in position by means of the dog p^{30} . In place of the vibrator I may use an interrupter or other circuit-breaking device. The test contact s^6 in Fig. 6 is connected to ground by the operation of the armature 222 of the relay R^7 and when the wiper s^2 of the advancing switch 40 engages the contact s^6 , current flows from the battery B through 215, R^7 , 223, 224, 225, s^2 , s^6 , 226, 227, 228, 222, 229 and to ground. The relay R^3 is actuated and the actuating circuit of the relay R^3 already traced is 50 broken at the contacts 27-27'. The switch therefore stops with its wipers resting on the conductors leading to the trunk 30-31. It will be seen that the action of this switch is purely a selective one and entirely automatic. The closure of the contacts 230'-231' of the relay R^3 closes the circuit of the signal lamp L, said circuit being from battery through 215, 232, 230', 231', L, 233, 234, 235, 236, 237 and ground.

60 I may also provide aural signals for notifying the operator of a call. Thus, a buzzer, howler or similar device may be arranged in parallel with or in place of the signal lamp L. In Fig. 6^a I have shown a buzzer B^2 65 provided with a primary and secondary

winding w' and w^2 respectively. One terminal of the primary winding is connected to the conductor 231' through 231^a, the other terminal being connected to the conductor 233 by means of the wire 233'. The terminals of the secondary winding w^2 are connected to the two inner contact springs 263^a and 264^a of the listening key O. These springs are normally in contact with the springs 263 and 264. The operator's receiver R^a is connected by means of the wires 266^a and 267^a to the terminals of the springs 263 and 264 respectively. The receiver is in circuit with the secondary coil 268^a, the transmitter T^a being in circuit with the battery B^a and the primary coil 269^a. A spring 270^a provided with a soft iron armature 271^a is arranged in proximity to the core 272^a of the buzzer so that when the armature is attracted it breaks the circuit 70 through the primary coil w' through the opening of the contacts at 273^a and 274^a. The primary coil w' of the buzzer being in parallel with the lamp L causes the actuation of the armature 271^a which is immediately perceived in the operator's head set. When the listening key is pressed the head set is cut out by the opening of the contacts between the springs 263 and 263^a and 264 and 264^a and the operator's set is connected 90 with the wires 249 and 251. The buzzers are preferably mounted on the operators' transmitters but they may be mounted individually in boxes like telegraph sounders.

The use of the aural signal I consider an 100 important feature of the present invention. As has been already explained the part played by the operator in this system is simply to answer calls, to set up the proper numbers on the keys and to start the operation of the automatic switches and relays for effecting the desired connections. By the use of a buzzer, blind operators can be employed, and in fact the system is particularly adapted for the employment of the 110 blind. It is a well known fact that where one sense is destroyed another sense is quickened. Blind persons generally have the 115 senses of hearing and touch developed to a high degree. The connection of the buzzer to the head set would insure the positive knowledge of the operator that a call had been received, but with the buzzer mounted on the operator's transmitter it would not always be necessary to connect it with the 120 head set. In fact where breast-plate transmitters are used the vibration of the buzzer would be instantly perceived without any connection whatever with the head set. I also contemplate mounting the buzzer or its 125 equivalent device on the person of the operator or on the desk, so that the vibrations may be felt without the necessity of listening. This is for some reasons preferable, one being the avoidance of disagreeable vi- 130

brations communicated to a sensitive ear, which might for the moment deaden the sense of hearing. By mounting the buzzer on the desk or key-frame, the operator can 5 receive the vibrations through the fingers.

The relay R^4 is in parallel with the signal lamp and is also actuated by the closure of the contacts 230'-231', current flowing through these contacts from battery, over 10 the path traced, through 238, R^4 and ground. The pulling up of the armature 224 of the relay R^4 breaks the test circuit but does not deenergize the relay R^3 which is locked through the circuit 239, 240, 241, 15 236, 237 and ground. When the armature 27 of R^3 pulls up the relay R^{10} (Fig. 5) is energized, current flowing from battery B, (Fig. 6) 215, 216, 27, 245, 244, 243, 242, 241, 20 s^5 , s^8 252, R^{10} and to ground. Thereupon the trunk wires 15 and 16 are broken at the contacts 253-254, and the trunk wires 18 and 19 are broken at the contacts 255 and 256. The armature 257 of the relay R^{10} having pulled up the relay R^9 is energized 25 current flowing from battery (Fig. 5) through 200, 201, 202, 258, 257, 259, R^9 , 221, 214, 213 and ground. The armature 203 of the relay R^9 in pulling up removes battery from the wires 57 and locks the relay R^9 by its engagement with the contact 260. The movement of the armature 27 of the relay R^3 in Fig. 6 while cutting off the vibrator connects battery to the next idle operator's set by means of the conductor 261. It will be observed that the 30 wire 240 leading from the contact 239 of the relay R^3 is extended into Fig. 7 and is connected with the pen q^x of the wheel Q^x , the latter being connected to ground through the conductor 246.

40 On perceiving the lighting of the signal lamp the operator presses her listening key O, thereby opening the contacts 242-243 and closing the contacts 262-263 and 264-265. The relay R^{10} momentarily retracts and the operator's set is connected to the sleeve side of the trunk through 262, 263, 249, 248, s^4 , s^9 , 266 and contact 255; and to the tip side of the trunk through the contacts 264, 265, 251, 267, s^3 , s^7 , 268 and contact 253. The operator then inquires the number wanted, which in this case I have assumed is 2312. She now presses the key k^2 of the set K' , the key k^3 of the set K^2 , then k^4 of the set K^3 and k^5 of the set K^4 . 45 These keys are all of the locking type already described and when pressed remain locked until liberated by the depression of another key in the same row. The key k^2 of the set K' connects the conductor 270 with the pen q' of the wheel Q^2 by means of the wire 74. Similarly, the key k^3 of the set K^2 connects the pen q^2 of the wheel Q^3 with the wire 270 by means of the conductor 75', the key k^4 of the set K^3 connects the pen q^3 50 of the wheel Q to the conductor 270 by

means of the wire 74' and the key k^5 of the set K^4 connects the pen q^4 of the wheel Q^2 to the conductor 270 by means of the wire 72'. The operator now depresses the starting button K^s . This operates the relay R^6 in Fig. 6, current flowing from battery B (Fig. 6) through 215, 271, R^6 , 272, K^s , 273 to ground. The relay R^6 is locked, the locking circuit being through the closed contacts 274, 275, conductor 276, 70 pen q^6 of the wheel Q^6 , and (if the pen is not on the insulating strip s) to ground through the wire 246. The operation of the relay R^6 causes the relay R^5 to pull up, the actuating circuit of the latter relay 75 being from battery B through 215, 271, R^5 , 277, contact 278 and ground.

The movement of the armatures 279 and 280 of the relay R^5 connects the wipers s^3 and s^4 with the wires 281 and 282 respectively, through the contacts 283 and 284 of the relay R^6 when the latter is deenergized. It will be noted, however, that at first these contacts are open due to the energization of the relay R^6 . 85

The wheel Q^6 revolves in the direction indicated by the arrow. Now, when the insulating strip s of the wheel Q^6 comes underneath the pen q^x , the locking circuit of the relay R^5 which is through the wire 240 is 90 momentarily broken. No effect, however, is produced because the relay R^6 is up and the wire 277 still closed to ground. The insulating strip now comes under the pen q^x and the locking circuit of the relay R^5 which is 95 through the conductor 276 is broken. In the meantime the insulating strip has passed from beneath the pen q^x , and the locking circuit of the relay R^5 is again completed. 100

The tooth t^2 of the wheel Q^2 together with 105 the teeth on the remaining wheels of the set now come in contact with their pens q^2 , q^3 , q^4 , etc. The wheel Q^2 , however, is the only one which is active, the others being cut off by the open contacts of their respective keys in the sets K' , K^2 , K^3 , K^4 . The pen q' of the wheel Q^2 is connected by the wire 74 and the closed key k^2 of the set K' to the wire 270. Two impulses are thus sent to the vertical magnet V^m (in Fig. 5), the current for the actuating impulses flowing from battery (Fig. 7) through 303, b , C^m , 304, 305, t^2 , q' , 74, 73, 73', 270, 281, 283, 279, 267, s^3 , s^4 , 268, 16, 296, 294, 295, V^m , ground. Thereupon the wiper 117 of the switch X 110 is stepped up to the second pair of contacts. 115

The tooth t^2 of the wheel Q^2 now comes into engagement with the pen q^x thereby causing the energization of the relay R^{12} , 120 the energizing current being through battery B (Fig. 5), 200, R^{12} , 285, 255, 266, s^9 , s^4 , 248, 280, 284, 282, pen q^x of the wheel Q^2 and to ground. The pulling up of the armature 286 of the relay R^{12} actuates the relay R^{11} , the actuating circuit for the latter 130

being from battery through 200, 286, 287, R¹¹ and ground. The relay R¹¹ is locked, the locking circuit being from battery, 200, 201, 202, 203, 260, 259, 288, 289, R¹¹ and to ground. The movement of the armature 294 of the relay R¹¹ cuts off the vertical relay V^m of the switch X which is normally connected to the trunk 30, by means of the conductor 295, contact 294 and conductor 296. An extra armature 297 on the relay R¹¹ connects battery to the armature 298 of the relay R⁸ through the conductor 302, this armature having previously pulled up so that contact with the wire 300 leading to the tip side of the cord circuit is broken. The movement of the armature 290 of the relay R¹² places current on the wires 108 and 109 leading to the tens relay E and the units relay F, respectively, in Fig. 8, these 20 relays pulling up and locking. The energizing circuit for the relay E is from battery (Fig. 5), through the wire 108, as already traced, and through 310, continuation of 310 in Fig. 9, to ground through the 25 closed contacts of the relay D^y. The energizing circuit of the units relay F' is from battery through 109, F', 311, continuation of 311 in Fig. 9 and to ground through the closed contacts of the relay D^y. The locking circuit of the tens relay E is from battery (Fig. 9) and first by wires 312, 325, 315, armature 314, 316, 348 to wire 317; and afterward when relay R¹⁶ is energized by the following path: 312, 313, 314^a, 315^a, 348^a, 317, (into Fig. 8) to relay winding and contact 319 to ground back to battery, that of the units relay F being over the path traced to the wire 317, thence by 320 through F and to ground through the armature 321. The closing of the contacts of the units relay energizes the relay D^y of Fig. 9, the energizing current being from battery through 312, 325, D^y, 349 in Figs. 8 and 9, wire 350—351 and ground.

45 The same impulse from tooth t^o and pen q^r which puts current through wire 292 on the contacts 108 and 109 of switch X, also energizes the release magnet R^m over the branch wire 298. Magnet R^m pulls up and 50 engages its hook with the detent 128 but does not draw back the same until the tooth t^o has passed the pen q^r and the current flow ceases, when the armature lever 132 pulls back the detent 128 and the switch stem 115 drops by gravity to its normal or inoperative position.

55 The set of number wheels Q', Q², Q³, etc., having made a quarter of a revolution before the tooth t^o and pen q^r make contact, their teeth thereafter come in contact with the set of pens q². The key k² of the set K² is down, and consequently the wheel Q³ is the active one, the others being disconnected. Three impulses are sent out from the wheel 60 Q³ over the wires 270 and 281 and through

the trunk conductor 30 (Fig. 5) and, since the relays E and F have pulled up, through their closed contacts 322 and 323 respectively, onto the trunk conductor 30^a in Figs. 8 and 9, through the relay R¹³ to ground. The relay R¹³ in turn pulls up three times. The movement of the armature 324 of the relay R¹³ closes the actuating circuit of the relay R¹⁶, current flowing from battery B (Fig. 9) through 312, 325, contact 326 of the relay R¹⁴, wire 327, 324, 328, R¹⁶ and ground. The movement of the armature 329 of the relay R¹³ places three impulses on the vertical magnet 2V^m of the switch X², current flowing from battery through 312, 325, 329, 330, contact 331 of relay R¹⁵, 332, 2V^m and ground. The actuation of the relay 2V^m steps the wiper 333 of the switch X² up to the third pair of contacts 334, 335. When the relay R¹⁶ is actuated it locks, the locking circuit being from battery through 312, 325, armature 336 of relay R¹⁴, 337, 338, contact 339, R¹⁶ to ground.

Referring again to Fig. 7 the tooth 2t^o of the wheel Q^r now comes into engagement 90 with the pen q^r, and the sleeve relay R¹⁴ in Fig. 9 is actuated, the actuating circuit being from battery B through 312, 313, wire 340, contact 341 of relay R¹⁶, 342, 343, R¹⁴, back on the trunk conductor 31^a, through 95 trunk 31 to wire 266, and thence to ground through the wheel Q^r. The actuation of the relay R¹⁴ places an impulse on the release relay 2R^m and at the same time connects the contacts 334 and 335 with the battery 100 through the conductors 312, 325, 336, 344. The pulling up of the armature 326 energizes the relay R¹⁵, the energizing circuit being from battery through 312, 325, 326, 345, R¹⁵ and ground. This relay is locked, the 105 locking circuit being from battery 312, 313, 315^a, 314^a, 348^a, 348, 316, 314, R¹⁵ and ground, a branch of this current is 346, 347, 348, controlled by relay R¹⁴. The actuation 110 of the armature 331 of the relay R¹⁶ breaks the circuit of the vertical magnet 2V^m. Current having been placed upon the wires 334 and 335 by the pulling up of the armature 336, the tens relay G² and the units relay H² of Fig. 10 are energized, the energizing circuit of the tens relay G² being from the wire 335 through 352 in Figs. 10 and 11, and 115 through the closed contacts of the relay D^z to ground. The actuating circuit of the units relay H², is from 353 in Figs. 10 and 11, through the closed contacts of the relay D^z to ground. The closing of the contacts 120 of the units relay H² actuates the relay D^z in Fig. 11, the actuating current being from battery B (Fig. 11), through 354, 355, D^z, 125 356 in Figs. 11 and 10, 357, 358 and ground. The relays G² and H² on pulling up, however, are locked, the locking circuit of the former being from battery through 354, 355, 359, contact 360 of the relay R¹⁷, 361, 362, 130

363³ in Figs. 11 and 10, 364, contact 365 and ground. The locking circuit of the units relay H² is from the wire 363 through 366, contact 367 and ground. An inspection of Fig. 11 will show that these locking circuits are controlled also through a contact 368 on the relay R¹⁸, and a short conductor 369 leading to the wire 363.

Now referring back to the first selection and considering the operation just described, the scheme of selection and connection appears clearly in its full form. As stated there is one of the sets of tens and units relays like that shown in Fig. 8 for each second trunk 30^a and 31^a adapted to coöperate in the same manner as the tens and units relays heretofore described for line selection, the contacts of each trunk 30, 31 being multiplied to the same contacts in similar groups of relays 1E, 2E, 3E, etc., of other trunks 30^a, 31^a. Each trunk 30^a, 31^a as shown connects directly to the contacts of the units relays of its set. Each trunk 30, 31 as shown connects directly through multiplied connections to corresponding pairs of contacts in the same tens relay of each trunk set. In the relay set of Fig. 8 provision is made for the connection of 25 trunks 30, 31. Each group 1E to 3E, etc., to which the trunks 30, 31 are multiplied has a like capacity. As in the case of the primary connection of the calling lines 500, 501, to the answering ends of the idle trunks 30, 31, so the calling ends of trunks 30, 31 may be connected to any one of any group of idle second selector trunks 30^a, 31^a by the coöperation of the tens relay of its set containing terminals of first trunk 30, 31 and the associated units relay connected with the trunk 30^a, 31^a. In this coöperation the switch X in its functioning takes the place of the line relays of the lines in primary selection, the switch X controlling the corresponding circuits of the tens and units relays. By stepping the switch X to the second contacts 108 109 designating as stated the second or 2,000 group of trunks 30^a and 31^a, the switch X functions additionally as the line relays, for the second contacts of switches X control the relay sets of groups of trunks 30^a, 31^a in the 2000 group only. Similarly the first contacts control the identifying and connecting tens and units relays of the 1000 group of trunks 30^a, 31^a, the third contacts, those of the 3000 group, etc. Specifically speaking, the contacts of the switch X taken in order control each case the first tens relay and the first units relay (as for instance E and F), in each relay set of each group of trunks. Therefore, no matter in which thousands group a trunk 30^a, 31^a is selected, connection being made through the same tens and same units relay of the group, is made to the same trunk 30, 31 through the 65 associated multiplied connections. Simi-

larly the switches X' of trunks 30^a and 31^a function in connection with the relay groups G, 2G, etc. The selection of the groups here made is by the hundreds, the three hundred group being chosen as described, and one of its trunks 30^b and 31^b connected through the trunk identifying tens and units relays G² and H² respectively with the calling second trunk 30^a, 31^a. In a similar manner the conductors 334 and 335 from the fourth pair of contacts of switch X' will control corresponding relays 1G² and 1H² in the four hundred group of trunks 30^b and 31^b.

The set of number wheels has now completed a half revolution and the teeth are in contact with the set of pens q². The wheel Q' is the only active one this time and sends one impulse over the wire 281 to the trunk 30, thence on to trunk 30^a, and on to trunk 30^b which has now been connected through the medium of the tens and units relays shown in Fig. 10. The impulse sent out by the wheel Q' causes the momentary actuation of the relay R¹⁷. This impulse works the vertical magnet 3V^m of the switch X³ and causes the switch to step up to the first contact. The actuating circuit of the magnet 3V^m is from battery B (in Fig. 11), through 354, 368, 369, 362, 370, contact 371 of relay R¹⁷, 372, contact 373 of relay R²², 374, contact 375 of relay R¹⁹, 376, 3V^m and to ground. The pulling up of the armature 377 of the relay R¹⁷ causes the actuation of the relay R²¹, the actuating current being from battery through 354, 368, 369, 370, 378, R²¹, 379, 377 and ground. The relay R²¹ locks, the locking circuit being from the battery to the relay as traced, then through armature 380, conductor 381, contact 382 of the relay R²⁰ and to ground.

Following the impulse sent by the wheel Q' is a grounded impulse sent by the wheel Q^r. This grounded impulse operates the relay R¹⁸, current flowing from battery through 354, 383, 384, R¹⁸ and back on the trunks 31^b, 31^a and 31 to the wire 266 and to ground through the wheel Q^r. The actuation of the relay R¹⁸ energizes the relay R¹⁹, the actuating circuit being from battery through 354, 359, 360, 361, 370, R¹⁹, 385, armature 386 of relay R¹⁸ and ground. The relay R¹⁹ locks, the locking circuit being from battery through the relay as traced, thence through the armature 387, conductor 388 and contact 389 of the relay R²¹ (which is pulled up and locked) and to ground. The movement of the armature 368 of the relay R¹⁸ places current on the wire 390 leading to the tens relay U in Fig. 12 the actuating circuit of the relay U being from battery B through 354, 368, 391, 392, wiper 393, wire 390 in Figs. 11 and 12, relay U and to ground. Thereupon the relay U pulls up and closes the contacts leading to the first

group of ten lines associated with the trunk 30^b, 31^b and with other connector trunks of the same group. The set of number wheels has now reached the fourth pen q^4 , this time 5 the active wheel is Q² and two impulses are sent out over the tip side of the connected trunks in the manner already indicated and the relay R¹⁷ is again actuated twice. The pulling up of the armature 371 of the relay 10 R¹⁷ puts two impulses on the vertical magnet 4V^m of the switch X⁴ and the wiper of the switch is stepped up to the second terminal wire 394, the actuating current being from battery through 354, 368, 369, 362, 370, 15 371, 372, 373, 374, 375 and (since the relay R¹⁹ has pulled up) through 395, 4V^m and ground. The wheel Q² now grounds the sleeve side of the connected trunks and the relay R¹⁸ is again actuated, the actuating 20 current being over the circuit already traced. This time an actuating impulse is placed on the conductor 394 current being from battery through 354, 368, 391, 392, wiper 396, 394 (in Figs. 11 and 12), and through the 25 relay I' to ground. The relay I' through the actuation of its armature 397 closes the contacts at 398 and connects the trunk 30^b, 31^b with the conductors 399 and 400 leading to the wires 401--402, the latter being connected to all of the second pairs of contacts 30 in the relays U, U', U² of the set belonging to the trunk 30^b, 31^b. Since the tens relay U has pulled up, the wires 401 and 402 are now connected with the lines 403, 404 of the 35 wanted subscriber.

As soon as the trunk is connected with a line the relay R²² in Fig. 11 is actuated, the actuating current being from battery through 354, 383, R²², 415, through the sleeve 40 side of the trunk 31^b and through the subscriber's cut-off relay to ground. The actuation of the relay R²² through the pulling up of its armature 416 energizes the release magnets 3R^m and 4R^m, current for the former being supplied from battery through 354, 383, 412, 417, armature 418 of relay R²³, 419, 416, 420, armature 421 of relay R¹⁹, 422, 423, 3R^m and ground; the circuit for the relay 4R^m being from battery to the wire 423 45 over the path just traced and thence through the magnet 4R^m to ground. Both of these magnets pull up and are in condition for immediately releasing their respective switches when their actuating circuits are 50 broken. It will be noticed that the armature 421 of the relay R¹⁹ controls the actuating circuit of these two release magnets. Again referring to Fig. 7 the insulating strip s of the wheel Q² now comes under the pen q⁴. 55 This breaks the locking circuit of the relay R¹⁹ and its armatures fall back. This breaks the connection of the number wheels to the tip side of the trunk 30 and also the connection from the wheel Q² to the sleeve side of 60 the trunk so that any further contact of the

teeth of these wheels with their respective pens does not produce any effect, and although the wheels continue in motion, they are cut off completely from the trunk.

Both of the relays R⁶ and R⁶ having been 70 deenergized, the locking circuit of the relay R³ is broken and its armature 27 falls back into engagement with the contact 27'. This immediately places the operator's set in condition for answering another call since the 75 battery is now connected with the relay R² which is actuated on the pulling up of a relay R⁷ in any one of the primary trunk circuits. (Figs. 5 and 14.) As soon as a connection is effected with the wanted subscriber's line, and before the sleeve relay R¹⁸ has time to drop back, a test is placed on the line and if it is busy the connector circuit in Fig. 12 is restored to its normal condition. The means by which this is done is as 80 follows: If the called subscriber was the originator of a previous call his tip relay corresponding to the relay R⁸ (in Fig. 5) will be connected to his multiple terminals on the tip side of the trunk. It will be observed that this relay is grounded. As soon as the connection is effected with his multiple line terminals current will flow from the battery of the calling line (see Fig. 11) through 354, 359, 360, 361, 370, 378, 405, R²³, 95 406, armature 407 of relay R¹⁸, 408, over the tip side of the connected trunks and to ground through the relay already connected corresponding to the relay R⁸. Thereupon the relay R²³ in the calling subscriber's connector circuit (Fig. 11) pulls up and locks, the locking circuit being from battery through the relay as already traced, thence by the armature 409, through 410, R²⁰ and ground. The movement of the armature 100 411 of the relay R²³ connects the busy back B^b to the tip side of the calling subscriber's line and he will get the characteristic buzzing sound which notifies him that the line is busy. A path for current through 105 the busy back may be traced from battery B (Fig. 11) through 354, 383, 412, B^b, 411, 418, 30^b, 408, 407 (the relay R¹⁸ having by this time retracted), 414 and through the relay R²⁰ to ground. The energization of the relay R²⁰ through the pulling up of its armature 382 breaks the locking 110 circuit of the relay R²¹ which thereupon falls back. The retraction of the armature 389 of the relay R²¹ breaks the locking 115 circuit of the relay R¹⁹ which then falls back. The retraction of the armature 421 of the relay R¹⁹ breaks the actuating circuits of both the magnets 3R^m and 4R^m of the switches X³ and X⁴, respectively. 120 The deenergization of these magnets causes the restoration of the switches to their normal inoperative condition. Since the connector relays in the sets U and I (in Fig. 12) are energized through the switches X³ 125 130

and X^4 respectively, these relays retract when the switches are restored. The calling subscriber on hearing the characteristic sound of the busy back thereupon hangs up his receiver and clears out the connections already effected in the manner hereinafter explained. In case the called subscriber should have been called previously his sleeve relay corresponding to the relay R^{20} of his connector circuit will be connected with the tip side of the connector circuit and current will flow from battery (Fig. 11) through 354, 368, 369, 370, 378, 405, R^{23} , 406, 407, 408, through the tip side 30^b of the trunk, 15 onto the tip side of the trunk of the connector circuit of the called subscriber and to ground through his tip relay corresponding to R^{20} . This actuates the relay R^{23} and the restoration of the switches X^3 and X^4 20 is accomplished precisely in the same manner as that already shown in connection with the test when the wanted subscriber had originated a previous call.

In case the wanted line is not busy the energization of the relay R^{22} closes the circuit of the ringing relay R^{24} , the energizing current for the latter flowing from battery B through 354, 383, 412, 417, contact 418 of the relay R^{23} , 419, 416, 420, 425, armature 30 426 of the relay R^{20} , 427, R^{24} , interrupter C^o and ground back to battery. The interrupter C^o may be arranged to revolve at any given rate so as to actuate the relay R^{24} intermittently. At each actuation of the relay, its armatures 428 and 429 are attracted, thereby breaking the trunk circuits 30^b and 30^a and connecting the ringing generator G^r directly to the tip side 30^b and to the sleeve side 31^b through the resistance w . The ringing circuit is from the generator through one side of the trunk and a connected line circuit, through the subscriber's ringer and back on the other side. When the called subscriber answers, his talking circuit is 45 completed from battery through the relay R^{22} , through the sleeve side of the trunk and line, through his instrument, back upon the tip side of the line and connected trunk, and to ground through the relay R^{20} . Thereupon the relay R^{20} pulls up and the movement of its armature 426 breaks the circuit of the ringing relay R^{24} . This can only happen during the interval between rings when the relay R^{24} is deenergized. 50 The movement of the armature 382 breaks the locking circuit of the relay R^{21} which falls back. The retraction of the armature 389 of the relay R^{21} breaks the locking circuit of the relay R^{19} . The retraction of the armature 421 of the relay R^{19} cuts off the battery circuit through the wire 422 which supplies current for the actuating circuit of the magnets $3R^m$ and $4R^m$. But it will be noticed that the armature 426 of the relay 55 R^{20} in pulling up connects the wire 423 with

the wire 420 by means of the conductor 430, armature 426, and wire 431. Thus the actuating circuits of the magnets $3R^m$ and $4R^m$ are continued.

The talking circuit of the calling subscriber is from battery B (in Fig. 5) through 200, 201, R¹, 17, and back over the connected trunk conductor 31 through the subscriber's telephone, on the tip side of the connected trunk 30, through the tip relay R^8 and to 75 ground.

After conversation has ended the clearing out is automatically accomplished by the mere hanging up of the receivers of the subscribers. Considering the connector circuit in Fig. 11, when the called subscriber hangs up his receiver, he deenergizes the tip relay R^{20} . The retraction of its armature 426 breaks the actuating circuit of the magnets $3R^m$ and $4R^m$ and on the retraction of 85 these magnets the dogs 432 and 433 are withdrawn and the switches are restored to their normal position of disconnection. Thereupon the connector relays of Fig. 12 are deenergized and the connections are broken 90 in the manner already indicated. The breaking of the trunk circuit at the relays I and U deenergizes the relay R^{22} which falls back.

When the calling subscriber hangs up, the relay R^8 retracts. Thereupon the sleeve 95 side 18 of the trunk is grounded through the conductor 301 and the armature 299 while battery current is placed on the tip side of the trunk through the conductor 300, armature 298, conductor 302, armature 297, 201 100 and 200. The simultaneous placing of battery on one side of the line and of ground on the other is for the purpose of clearing out when the calling subscriber has hung up and is equivalent to short circuiting the two 105 sides of the trunk. The movement of the armature 205 of the relay R^8 breaks the locking circuit through the wire 57 and the units relay P (in Fig. 4) and the tens relay N (Fig. 2) are deenergized thereby breaking 110 the connections controlled by their armatures. This breaks the actuating circuit of the cut-off relay M' which lets go.

Referring again to Fig. 5, when the battery is connected to the tip side of the trunk 115 through the retraction of the armature 298 of the relay R^8 , current flows over the tip side of the connected trunks in Figs. 5, 8, 9, 10 and 11 and through the tip relay R^{17} and ground. At the same time through the 120 action of the armature 299 in Fig. 5 the ground placed on the sleeve side of the trunk results in a current flow from battery B (Fig. 11) through 354, 383, 384, R^{18} , back over the connected trunk in Figs. 10, 9, 8 125 and 5 and to ground. The simultaneous actuation of the two relays R^{17} and R^{18} and the simultaneous pulling up of the armatures 368 and 360, breaks the locking circuit through the wire 368 whereupon the tens 130

relay G and the units relay H retract, (Fig. 10) thus breaking the trunk connections controlled by their respective armatures. The breaking of the contacts between the wires 358 and 357 at the relay H in Fig. 10 breaks the actuating circuit of the relay D^x which thereupon falls back to its normal position.

The same impulse which is placed on the tip side of the trunk to work the relay R¹⁷ in Fig. 11 causes the actuation of the relay R¹⁸ in Fig. 9 and by the movement of the armature 329 breaks the locking circuit of the relay R¹⁶. Thereupon the armature 314^a of the relay R¹⁶ retracts and breaks the circuit 15 through the locking wire 317 leading to the units relay F and the tens relay E in Fig. 8. These relays let go and the opening of the contacts 351 and 350 breaks the locking circuit 349 of the relay D^y which falls back, 20 thus restoring the whole system to its normal condition.

In the foregoing description of the operation by which one subscriber is connected with another I have assumed that all the 25 connective apparatus is idle. I now wish to show how the idle trunks may be brought into use successively so as to handle the calls as they come in. Referring now to Fig. 13 let us assume that the trunk 30—31 is in use. The relay R⁷ has pulled up in series with the relay R⁸ as heretofore explained. The relay D^x controls the actuating circuits of the tens and units relays corresponding to the trunk 30—31 and when its armature is 35 attracted the actuating circuits are broken, the relays, however, remaining locked on the common locking wire 57 as already explained. The pulling up of the armature 207 of the relay R⁷ puts battery current on the relay 1D^x of the next trunk 130—131 through the conductors 201, armature 207, 40 208, 440, armature 441 of relay 1R⁷ of the trunk 130—131, 442, 1D^x and ground. Thereupon the relay 1D^x is actuated. It will 45 be noticed, however, that the actuation of the relay 1D^x connects the actuating wires of the tens and units relays pertaining to the trunk 130—131 with ground, in other words, it puts these actuating wires in the same 50 condition that the similar wires in trunk 30—31 were originally. Since all of the remaining trunks have these actuating wires broken at the relays D^x, none of them can be brought into use except when put in condition for use by the action of the relay D^x belonging to a previous trunk, or by the action of an independent switching device performing the same function.

If a call should now come the trunk 60 130—131 would therefore be selected and after the tens and units relays had pulled up and locked on the common locking wire 57', corresponding to the wire 57 of trunk 30—31, the subsequent actuation of the relay 1R⁷ breaks the actuating circuit of the

relay 1D^x through the movement of its armature 441. Thereupon the relay 1D^x lets go breaking the actuating circuits of the tens and units relays. The armature 443 of the relay 1R⁷ puts battery current on the relay 2D^x of the next trunk 230—231 through the conductors 201, 206, 205, 444, 443, 445, 446, 447 of the relay 2R⁷, 448, 2D^x and to ground. The relay 2D^x pulls up and connects the actuating wires of the tens and units relays corresponding to the trunk 230—231 with ground, thereby placing the trunk 230—231 in condition for a call. When the call comes in the relay 2R⁷ is energized and breaks the circuit of the relay 2D^x which falls back and breaks the actuating circuit of the tens and units relays. The latter are, however, locked through the common locking wire 57² corresponding to the locking wires 57' and 57 of the previous trunks 130—131 and 30—31. The movement of the armature 449 of the relay 2R⁷ puts battery current on the relay 3D^x of the next trunk 330—331 in a manner similar to that already described, and so on. Thus it appears that the idle trunks are selected consecutively as the calls come in and that no trunk which is in use can be interfered with by any of the calls.

Fig. 14 illustrates the method of distributing the calls among the various operators. It will be seen from this figure that the several trunks 30—31, 130—131, 230—231, etc., have multiple connections to the operators' sets which are controlled jointly by the relays R⁷ and R⁹. When a call comes in on any one of the trunks the operator's set Z² at the bottom of the figure will first come into use, the actuation of any of the relays corresponding to the relay R⁷ serving to energize the relay R⁹, which is normally connected to the battery through the wire 217' and the armature 27 of the relay R⁹. The actuation of the starting relay R², causes the intermittent action of the magnet R² in the manner already described. As soon as the actuating current is put upon the magnet R² the switch s' is stepped around until the wipers come onto the contacts of a calling line, when the relay R⁹ is energized and the pulling up of its armature 27 connects the battery with the relay R²² through the conductor 460, armature 461, and conductor 466. Thus the second switch of the set Z² is in condition for receiving the next call.

When a second call comes in, the second set Z² will be brought into operation through the pulling up of its starting relay R²². The pulling up of the armature 337' of the relay R²² puts battery current on the magnet 1R², its action being similar to that of the armature 221' of the relay R². The relay R²² is locked through the medium of another armature 338' and the conductor 130

339'. Now if the set Z' should be restored to its normal condition before the numbers have been sent by the second set Z^2 the relay R^{22} would not be dependent upon the actuation of the relay R^3 for its current, but would derive it through its own armature 338', through 339', 461, 466 and thence by wire 219 to ground. In a similar manner the set Z^2 is brought into operating condition by the pulling up of the armature 340' of the relay $1R^3$ of the set Z^2 . It will be seen that when any one set is in operation and the impulses are being sent in, it cannot receive another call until its relay (corresponding to R^3) has retracted and this is only at the end of the series of impulses. From the above description it will be apparent that the calls will be automatically distributed among the operators, thus providing each operator with the same amount of work that is given to every other operator.

I have described herein a method of and apparatus for connecting the operators' key sets to the trunk through driven switches. It is to be clearly understood that this is variable at will, and that relays or other devices may be employed instead of the switches. For example, the apparatus and circuits shown in Figs. 12 to 21 inclusive, of my co-pending application, Serial No. 383,875, filed July 15, 1907, may be employed instead of that in Figs. 7, 6, and 5 hereof. The preferred form of relay secondary selector is that shown in Figs. 12, 16, 20 and 21 of the aforesaid co-pending application, and in using the same herein certain detail adaptations of the trunk circuit of Fig. 12 in the co-pending case must be made to fit those in Fig. 5 herein. Thus the cut-off relay R^{10} should be replaced by two relays such as R^4 and R^5 of the prior case, accompanied by their listening relay R^6 . These and other necessary changes will be so apparent to anyone skilled in this art as to need no further description.

Having thus described my invention what I claim and desire to secure by Letters Patent of the United States is:

1. In a telephone exchange system, subscribers' lines, connective links therefor, automatic connective apparatus comprising switches for selecting successive groups of links and relays associated with said links for determining the extension of the connection through an idle link in a selected group with means controlled by an operator for initially actuating the automatic connective apparatus.

2. In a telephone exchange system, subscribers' lines, connective links therefor less in number than the number of lines, automatic connective apparatus comprising switches for selecting successive groups of links and relays responsive to the action of

said switches for selecting and extending the connection through an idle link in a selected group, with means controlled by an operator for initially energizing said automatic connective apparatus.

3. In a telephone exchange system, subscribers' lines, connective trunks therefor less in number than the number of lines, automatic connective apparatus comprising connecting relays and governing step-by-step switches therefor arranged to be operated by current impulses for selecting trunk groups and means controlled by an operator for transmitting a predetermined number of impulses to said automatic connective apparatus to effect the desired connection.

4. In a telephone exchange system, subscribers' lines, connective trunks therefor less in number than the number of lines, automatic connective apparatus comprising connecting relays and governing step-by-step switches therefor arranged to be actuated by current impulses, impulse sending apparatus and means controlled by an operator for energizing said switches through current impulses from said sending apparatus whereby desired trunks are selected and the connection with the wanted subscriber effected.

5. In a telephone exchange system, subscribers' lines, connective trunks therefor less in number than the number of lines, primary automatic means for selectively connecting the calling subscriber with an idle first trunk, means associated with the selected trunk for selecting a group of second trunks to advance the connection, additional means associated with the second trunks but controlled by the preceding group selective means for connecting with the first selected trunk and means controlled by an operator for initially actuating the trunk selecting means.

6. In a telephone exchange system, subscribers' lines, connective trunks therefor less in number than the number of lines, automatic means for selectively connecting a calling subscriber with an idle trunk, means associated with the selected trunk for selecting a group of trunks to advance the connection, additional means associated with the selected group but controlled by the preceding group selecting means for selecting and connecting an idle trunk of the group and an impulse sending device controlled by an operator for actuating both of the trunk selecting means.

7. In a telephone exchange system, subscribers' lines, connective trunks therefor less in number than the number of lines, automatic means for selectively connecting a calling subscriber with an idle trunk, means associated with the selected trunk for selecting a particular group of trunks to advance

- the connection, additional means associated with the selected group, but controlled by the preceding group selecting means, adapted to connect an idle trunk of the group, an impulse sending device, an operator's key set and means controlled by the keys for initially actuating the trunk selecting means. 8. In a telephone exchange system, subscribers' lines, connective trunks therefor, an impulse sending device associated with said trunks, automatic means for selectively connecting a calling subscriber with a trunk, means associated with the selected trunk for selecting a particular group of trunks to effect a further connection, additional means associated with the selected group but controlled by the said group selecting means for selecting and connecting an idle trunk of the group and means controlled by an operator for placing actuating impulses on the group selecting means and through connections effected by the latter to actuate the additional means and thereby effect a connection with a second trunk. 9. In a telephone exchange system, subscribers' lines, connective trunks therefor, tens and units relays for automatically connecting a calling subscriber with a first trunk, a switch associated with said first trunk and arranged to select a second group of trunks, tens and units relays also associated with said trunks and controlled by said switch for selecting a particular trunk of the second group to further extend the connection, said switch and said relays being under the control of an operator. 10. In a telephone exchange system, subscribers' lines, connective trunks therefor, automatic means for connecting a calling subscriber with an idle first trunk, automatic means controlled by an operator for connecting said first trunk with a second trunk, automatic means controlled by the operator for connecting said second trunk with a third trunk, and a pair of automatic switches and a group of tens and units relays for conjointly effecting the talking connection with the wanted subscriber. 11. In a telephone exchange system, subscribers' lines divided into groups, connective links therefor comprising trunk circuits, automatic means for selectively connecting a calling subscriber with an idle first trunk, automatic means for effecting a further connection of the first with a second idle trunk, automatic means for effecting a connection of the second with a third idle trunk the last two means being controlled by an operator, means associated with said third trunk for selecting a group of terminals containing the line of the called subscriber and separate means associated with the third trunk for selecting the member in the group corresponding to the line of the called subscriber and effecting a final talking connection. 12. In a telephone exchange system, subscribers' lines divided into groups each group terminating in the contacts of a relay, connective trunks for said lines, automatic means for connecting a calling subscriber with a first idle trunk through the medium of said relays, automatic means for connecting said first trunk with the second idle trunk, automatic means for connecting the second idle trunk with the third idle trunk both of said automatic means being controlled by an operator, a pair of switches associated with said third trunk and arranged to select the group of terminals containing the wanted subscriber's line and a set of relays arranged to selectively effect the connection with the wanted subscriber of the group. 13. In a telephone exchange system, subscribers' lines, a plurality of connective trunks therefor, automatic means for connecting said lines with a first trunk, relays for effecting a further connection with a second trunk, and an automatic switch controlling the relays, said automatic switch consisting of a frame, a row of contacts carried by said frame, a rack bearing wipers adapted to effect engagement with said contacts and means for stepping the rack so as to engage any desired contact. 14. In a telephone exchange system, subscribers' lines and connective links therefor provided with selective switches, said switches each comprising the following instrumentalities: a U-shaped rectangular frame with a brace secured across the open end thereof, registering openings in the opposite legs of said frame, a weighted spindle or carrier reciprocating in said openings, ratchet teeth formed on said carrier, a pair of wipers projecting therefrom at right angles to its axis, bank contacts in the path of said wipers, an electromagnet with an armature lever and pawl for engaging said ratchet to reciprocate the spindle, and a detent also engaging the ratchet, with means for releasing the same to restore the switch. 15. In a telephone exchange system, a switch comprising the following instrumentalities: a contact bank having a straight row of contacts arranged intermediate of its ends, a U-shaped rectangular frame with the ends of its legs adapted to be secured to the ends of the said bank so as to straddle the contacts therein, a spindle or carrier adapted to reciprocate in said frame, a wiper mounted thereon and adapted to sweep over the bank contacts in its travel, an electromagnet adapted to advance the carrier and wiper step by step, a detent for retaining the same when so advanced, an electromagnet controlling said detent, and

- circuit connections for said electromagnets, having detachable coöperating contact members mounted on the bank and on the frame respectively.
- 5 16. In a telephone exchange system, a series of line circuits, and a trunking system for interconnecting the same comprising a plurality of link circuits arranged in percentage order and to be connected in series 10 with each other and with the lines, and relay connector groups constituting the switching terminals of the corresponding links.
17. In a telephone exchange system, a plurality of lines to be interconnected, and 15 a trunking system for interconnecting them comprising a plurality of connecting links,
- switching means constituting the terminal of a primary link arranged to connect said link with calling lines, and digital relay selective switching means constituting the 20 switching terminals of each of the connector links and arranged to connect the same in series and with wanted lines, together with means for selectively operating the relays of said switching means. 25

In testimony whereof I affix my signature in presence of two witnesses.

EDWARD E. CLEMENT.
